MANIFOLD FORM FEEDING AND HOLD-DOWN MECHANISM

John M. Riordan, Cleveland Heights, Ohio, assignor to Bonnar-Vawter, Incorporated, Cleveland, Ohio, a corporation

Application September 23, 1952, Serial No. 311,124

4 Claims. (Cl. 271—2.1)

This invention relates to feeding and hold-down mechanism, and primarily to such mechanism most particularly useful in conjunction with a collating machine.

In collating machines of the type to which this invention refers in availing of the same for incorporation therein, record sheets are provided in the form of a continuous web of paper, directed to the machine and interleaved with corresponding strips of transfer or carbon paper, all of the same being performed in a substantially continuous operation, and effecting an interleaving of a number of such record and carbon sheets, with the record sheets being maintained in aligned condition with regard to printed matter carried upon the surfaces thereof.

In order to maintain the record sheets with the printed matter on the same in aligned condition, it has been found that the same may be desirably effected by providing at one edge of the web, a plurality of longitudinally aligned holes which are suitably spaced so as to receive therein feed pins or fingers. It will be understood that the holes in the respective webs of record sheets are formed in relation to the printed matter appearing thereupon, and thereby aligning of the said holes, and the insertion of suitable pins therein so as to carry the webs through the machine, the printed matter may be maintained in aligned position as the collating operation proceeds. Further, during the collation of such webs, it is often highly desirable to cause the respective webs to be glued or otherwise fastened together by suitable adhesive and in order to maintain the webs in such condition after the adhesive has been initially applied, the fingers or pins are desirably maintained in contact with the feed holes above mentioned for a substantial period of time.

During the time after which the adhesive has been applied, and before the same has dried sufficiently for the proper maintenance of the respective webs in their thus aligned condition, it may in some instances require that the pins be in engagement with the feed holes and in entering and being retracted from the feed holes, not cause the webs to be mis-aligned or thus effect a mis-registry of the respective web.

Heretofore the use of feed holes involving the provision of pins on a continuous traveling member such as an endless belt, has oftentimes not been completely satisfactory, in view of the fact that as the continuous web or belt moves around its supporting members the pins are caused to enter the feed holes at an angle with respect to the same, and thus under certain conditions affect unfavorably the registration of the respective record sheets, and thereafter unduly enlarge the feed holes if registry has been changed, and thereby prevent proper manipulation of the assembled web for subsequent operations thereupon.

Further, previously it has been contemplated that in maintaining the respective webs of record sheets in condition, with the same being carried through the machine by the pins entered in the feed holes thereof, to maintain the respective webs in surface contact so as to secure the adherence thereof by means of the adhesive with

2

a flat hold-down member which, under many conditions in and of itself, unduly retards the movement of the upper record sheet with which the same is in contact and often affects certain of the other record sheets disadvantageously. It will be apparent that this results from the necessity for sufficient pressure to be applied by this hold-down bracket in order to secure the proper adhesion of the respective webs.

Further, previously in order to adjust the speed with which the feeding mechanism is operating, involving the pins therein, the same has been regulated by complicated means with respect to the speed of the balance of the machine, oftentimes resulting in an undue enlargement of the feed holes because of the variations in speed of the respective feeding unit and units through which the webs of paper have passed previously. It is therefore understandable that it would be highly desirable to have a readily adjustable arrangement so as to afford perfect registration and maintenance of proper tension of the web through the collating machine under all conditions.

It is therefore a principal object of this invention to provide a feeding mechanism involving an endless member upon which the pins are mounted for entering the feed holes of the webs being fed, and to effect insertion of and withdrawal of the pins in such a manner as to maintain the respective webs in proper registration and not enlarge the feed holes or otherwise distort the registration.

It is a further object of this invention to provide a feeding mechanism which involves a feed unit including therein a series of feeding devices connected to the endless member, which devices include members for engaging the feed holes in the paper web, and which may be inserted in and withdrawn from said feed holes in groups, and in substantially vertical direction so as not to provide a radial entrance of the pins into the feed holes.

It is a further object of this invention to provide a feeding mechanism which includes a feeding unit having therein a pair of sprocket members upon which an endless chain is mounted, the endless chain in turn being connected with a plurality of carriers, which carriers are formed with pins extending therefrom at right angles, the carriers in turn being engaged with a track which will cause the carriers to move in a substantially vertical direction, at one point in their traverse, and thus enter the feed holes in the webs of paper in a substantially vertical direction and without distortion or causing mis-registry of the respective webs.

It is a still further object of this invention to provide a novel hold-down unit, which unit is formed so as to adequately maintain the respective webs in their positions for the feed pins, and at the same time eliminate the braking effect transmitted to at least the upper one of the said webs so as to permit the maintenance of the webs in perfect registry throughout the machine.

It is a still further object of this invention to provide a novel adjusting arrangement, so as to vary the rate of feeding or movement of the feed pins with respect to the main drive of the machine so that a nicety of adjustment may be attained and perfect tension maintained on the web being fed through the machine.

An additional object of the invention, is to provide such an arrangement of adjustment that by actual adjustment of one of the members thereof, variation or change in speed of the respective members may be attained.

A still further object of this invention is to provide a feeding mechanism wherein a primary drive gear is availed of, which gear is helically cut in one direction, and engages an intermediate gear, a secondary gear having teeth thereon helically cut in the other direction also engages the intermediate gear, and by actually shifting the intermediate

gear, variations in the rotational relationship between the primary and secondary gears may be attained.

Other and further objects of this invention will be understood from a description thereof set forth in the specification, and shown in the drawings, wherein:

Figure 1 is a side elevational view of the mechanism of this invention, being partly in section.

Figure 2 is a top plan view of the mechanism hereof, showing the arrangement of the drive gearing and adjusting means therefor.

Figure 3 is an end view, taken from the left end of Figure 2, and being somewhat fragmentary in nature, showing the relationship between the drive gearing, the feeding unit, and the hold-down unit hereof.

Referring now to Figures 1 to 3 inclusive of the drawings, there is illustrated a drive gearing unit generally designated A, a feeding device designated B, and a hold-down unit generally designated C.

The feeding device B will first be described, and is shown as consisting of a frame designated 1, suitably mounted upon a frame 2 of the machine, the latter being shown partially. Mounting of the frame 1 is by means of the bolts and nuts 3, the frame 1 being comprised of substantially identical frame members 4 and 5, the frame member 4 designated the rear frame, and frame member 5 the forward or outer frame. The frame members 4 and 5 are provided with what may be called cam tracks 6 and 7 respectively, it being apparent from a consideration of the drawing that the cam tracks are to be substantially aligned, the reason for this being understood as the description hereof proceeds. The cam tracks 6 and 7 referred to, are formed in the faces of the respective frame members in the form of grooves of some substantial depth and width.

Intermediate the respective frame members 4 and 5, there is suitably mounted a feeding unit generally designated 8, said unit comprising a pair of sprockets 9 and 10. The sprocket 9 is suitably mounted on a shaft 11, carried in bearings formed in the frame members 4 and 5, the shaft 11 having at its rearward end a gear 12 which will be referred to as the secondary drive gear.

The other sprocket 10 is mounted on a suitable shaft 13, likewise supported in bearings formed in the respective frame members 4 and 5.

Suitably mounted on the sprockets 9 and 10, which are spaced from each other some distance apart, is an endless chain 14 of conventional construction involving the usual links and pintles therefor. Suitably connected to the chain 14, are a series of carriers 15. The carriers 15 are each formed as seen in Figure 1, with a body portion 16 and an offstanding leg 17a. The offstanding leg 17a is pivotally connected to a corresponding pintle of the chain 14, each of the carriers 15 being so connected, and in one example of the device, extending about the equivalent of 3 links of the chain. At the opposite end, the carriers 15 are each provided with a pair of rollers 17 which rollers 17 are adapted to engage in and operate in the cam tracks 6 and 7 previously referred to. It will be understood that the respective frame members 4 and 5 are suitably spaced so as to receive therebetween the chain 14 and sprockets 9 and 10, as well as the carriers 15, but that the rollers 17 extend into the tracks as previously mentioned.

Each of the carriers 15 is provided with a series of pins 18, in this instance there being 4 of the same, all of these pins being mounted in the carriers so as to extend at right angles therefrom.

As viewed in Figure 1, it will be noted that the cam track 6 substantially follows the general contour of the chain 14 mounted on the sprockets 9 and 10, but at the right-hand end of the feeding unit 8 the cam track 6 is formed with a cam lobe 19. This cam lobe 19 is formed so that as the particular carrier reaches that point, the end upon which the rollers 17 are mounted will move upwardly at the same rate as the offstanding end of the carrier 15, and thus the pins 18 on the carrier will move upwardly in a substantially vertical manner.

Thus, when a web of paper or record sheet is in the position at the right-hand end of the mechanism shown in Figure 1, further movement of the chain and thus the carriers 15 thereon, will cause the pins 18 to move into the feed holes provided in the web at the edge thereof, without any distortion of the holes, the pins moving simultaneously and in a vertical direction in contrast to a radial direction.

The movement above described is effected by reason of the fact that the arc designated by the line 20 having the arrows at opposite ends thereof, is equal to the arc 21, of a similar nature having arrows at its end. The arc of the line 21, is the arc of the pitch line of the sprocket 10 as will be understood, and thus the rate at which the connection with the chain 14 moves upwardly will be at the identical rate at which the rollers 17 at the other end of the carrier 15 move upwardly; thus effecting a vertical simultaneous movement of all of the pins 18 into engagement with the feed holes in the strip at the edge of the web being fed.

Thereafter, the cam track 6 is so arranged as to cause the carriers 15 to move or travel in a substantially level plane by the portion 22 of the cam track, until the carriers reach the other end of the feed unit. At the other end of the feed unit, an opposite movement to that previously described on the part of the pins 18 takes place. This is effected by reason of the fact that the arc indicated by the line 23 between the arrows at the left-hand end of Fig. 1, is equal to the arc indicated by the line 24 between the arrows. However, it will be apparent that the arc of the track 23 lies in an opposite direction to the arc 20 previously referred to, and thus as the end of the carrier 15 connected at 17a to the chain moves downwardly, likewise the rollers 17 of the opposite end of the carrier will also move downwardly simultaneously and thus withdraw the pins 18 in a vertical direction simultaneously from their positions in the feed holes of the web being fed.

Thereafter, the carriers 15 travel around with the chain 14, it being relatively immaterial what form the track takes during such travel until the same reach the opposite end where the action previously described will obtain. It will thus be apparent that the cam track 6 involves elements at one end thereof, including the arc 19, which cause the carriers to move as described, additional elements adjacent the same which cause the carrier to remain in its upraised position with the pins 18 engaging the feed holes, and subsequently additional elements of the cam track 6 are provided at the other end of the unit to retract or withdraw the pins.

Although the above description refers only to the cam track 6, it is to be understood that the cam track 7 is of identical configuration and is exactly located opposite the track 6.

It will be understood that a table 25, is provided, the same having a slot therein through which the pins 18 project, during the operation previously set forth, and from which the pins are retracted at the end of their travel movement.

In order to maintain the respective webs or strips of record sheets in contact when the same are engaged by the feed holes therein with the pins 18, the hold-down unit C is provided. The hold-down unit C, includes a longitudinally extending bracket 26, of L-shaped cross section, somewhat more clearly shown in Figure 3, one leg of the member 26 being pivotally supported at 27 on the table 25. The other leg 28 extends at right angles to the member 26, and has mounted thereon a plurality of rollers 29. The rollers 29 are closely spaced as seen in Figure 1, and include the grooves 30 in the peripheries thereof. The rollers 29 are preferably mounted upon ball-bearings or other anti-friction bearings, so as to rotate very freely and not to retard the movement of the upper strip or web of record sheets as the web passes

75 through the mechanism hereof.

It will be understood that the rollers 29 are provided with the peripheral grooves 30a so as to permit the pins 18 to move as required, and yet the peripheries 31a may remain in contact with the web so as to keep the same in position on the pins 18. A suitable adjusting bolt arrangement 32a is provided, so as to vary the tension of the rollers 29 upon the web, as required by different thicknesses of web and different conditions of operation.

Referring now to Figure 2 in the drawing, the drive gearing arrangement A will now be described. This mechanism A includes a main drive gear 30, suitably mounted on a drive shaft 31, the drive shaft 31 being in turn provided with sprocket 32, the sprocket 32 being driven from the main motor of the machine (not shown) at a predetermined speed. The gear 30 has teeth 33 thereon cut helically and in one direction so as to engage with helically cut teeth 34 upon an intermediate gear 35. It will be noted that the teeth 34 are cut near one side of the gear 35, and on the other side of the gear, other teeth 36 are helically cut in the opposite direction. The teeth 36 in turn engage with correspondingly helically cut teeth 37 on the gear 12, previously mentioned—the gear 12 being noted as the secondary gear.

The gear 35 is mounted upon a hub 38, see Figure 1, which hub 38 is in turn carried in a bracket 39. The gear 35 is adapted to freely rotate on the hub 38, the hub 38 being in turn fastened by a pin to an adjusting screw 41. The screw 41 is provided with a handle 42, the handle 42 being accessible for manipulation. The rear end of the screw 41 is engaged in a suitable threaded opening 41a in the frame 2. The bracket 39 previously mentioned, is formed so that the axial movement of the hub 38 may take place, and the same may thereafter be fixed by means of a screw 43 in the lower side thereof, effecting a clamping operation of the lower portion of the bracket.

With the foregoing in mind, in order to effect relative rotative changes of the sprocket 32 and the secondary gear 12 by means of which the feed unit 8 is driven, the gear 35 may be shifted toward and from the rear of the mechanism, by loosening the set screw 43 and thereafter rotating the handle 42. This will cause the gear 35 to move on its axis, and thus change the timing between the gears 30 and 12, within a narrow range of movement depending on the angle at which the respective helices are cut on the gears. Thus, when it is desired to change the timing, the above operation may be effected, so as to cause the movement of the pins 18 at a rate to correspond with other mechanism from which the mechanism herein is receiving the web of material, and thus prevent mis-alignment of the pins with respect to the feed holes as will be understood.

As shown in Figure 2, a fragment of a web of manifolded forms is indicated at D, the same being provided with the feed holes 45 near one edge, which feed holes 45 are to be engaged by the pins 18 previously mentioned.

The collating of the respective webs and the subsequent movement of the web D as shown in Figure 2, so as to provide a manifolded form arrangement, is thus effected by means of the pins 18 which move in a vertical upward direction so as to project above the table 25, and thereafter move along the table 25 while the adhesive is drying between the respective strips of the web, and thereafter the pins 18 may be retracted by the means set forth so as to be withdrawn from the position above the table 25, without affecting adversely the alignment of the respective record sheet webs or distorting the holes 45 therein.

I claim:

1. In mechanism of the class described for feeding strip material including paper webs having feed holes in an edge thereof, in combination, a frame, a table on said frame, a feeding unit supported by said frame for feeding the strip material along the table comprising sprockets and an endless chain carried thereby for travel movement therearound in one direction beneath said table, drive means for said unit, a series of feeding devices separate from said chain, pivotally connected to said chain so as to extend outwardly with respect thereto for movement therewith, said devices having one end free of and in trailing position with respect to the direction of travel of said chain, said devices having feed hole engaging instrumentalities thereon and guide elements on said frame spaced outwardly with respect to said chain, said one end of each of the devices having a part in constant engagement with said elements to effect vertical movement of the instrumentalities during traverse of the chain around a sprocket and simultaneously project the same above the table at right angles.

2. The combination as claimed in claim 1, wherein the feeding devices comprise carriers pivotally connected at only one end to the chain, the free end of said carriers being engaged with the guide elements which comprise a cam track spaced outwardly of said chain having a section formed to raise said free end of each carrier during travel movement thereof at the same rate as the end of the carrier connected to the chain, to cause the vertical movement stated.

3. The combination as claimed in claim 2, wherein the section mentioned is a first section near one end of the table, a second section extends beneath and substantially parallel to the table, said second section maintaining each carrier in raised position during travel therealong, and a third section of the track near the other end of the table at a distance from the first section is formed to lower said free end of each carrier at the same rate as the end of the carrier connected to the chain, to cause simultaneous lowering of feed instrumentalities thereon at right angles to the table.

4. The combination as claimed in claim 1, wherein the feed hole engaging instrumentalities comprise a plurality of pins extending at right angles from each feeding device, said pins being adapted to engage in aligned feed holes in a plurality of paper webs, and a hold-down unit is mounted above said table and includes a plurality of aligned rollers having peripheral grooves formed therein, the peripheries of said rollers being adapted to engage the surface of one web of paper and the pins extend into said grooves during travel movement thereof.
